O. PETERSON

ATTACHMENT FOR JACKS

Filed Jan. 9, 1925

Patented Nov. 3, 1925.

1,559,910

UNITED STATES PATENT OFFICE.

OSCAR PETERSON, OF WILLISTON, NORTH DAKOTA.

ATTACHMENT FOR JACKS.

Application filed January 9, 1925. Serial No. 1,390.

To all whom it may concern:

Be it known that I, OSCAR PETERSON, a citizen of the United States, and a resident of Williston, in the county of Williams and State of North Dakota, have invented certain new and useful Improvements in Attachments for Jacks, of which the following is a specification.

In most forms of lifting jacks as at present constructed, it is necessary to place a jack head underneath the object to be lifted in order to employ the same. An object of this invention is to provide an attachment for any ordinary lifting jack which will enable the same to be used for the purpose of lifting objects which lie at a lower level than the jack head itself.

Another object is to provide such a device which shall be simple and economical in manufacture and may be applied to a jack head of practically any type.

A further object of the invention is to provide such an attachment which can be turned to various angles for the purpose of lifting articles or exerting force thereon in other than a perpendicular direction.

Other objects will be apparent from the following detailed description and the appended claims.

30 In the drawings:

Figure 1 is a perspective view of a conventional form of jack having the attachment in position and shown as lifting a rail.

Figure 2 is a side elevation of the jack attachment with jack head shown in dotted lines.

Figure 3 is a vertical section through the device.

Figure 4 is a side elevation of a modified form.

The drawings illustrate a jack head A supported by a base B and operated by a handle C. These parts in themselves form no part of the invention and the form shown is to be regarded as merely illustrative and as in no way limiting the application of invention since the attachment is particularly designed to be employed in connection with substantially all forms of lifting jacks.

50 The attachment itself comprises a plate 1 to which is attached by rivets 2 a second plate 3. This plate has at its ends down-turned ears 4 and through each pair of ears passes a bolt 5 held in position by a nut 6. At one end of the device there passes freely

through the plates a bolt 7 having a screw threaded portion 8 which is engaged by a nut 9 to prevent withdrawal of the bolt. This bolt terminates in a relatively large eye 10 at its lower end. Two hook members 11 are provided with eyes 12 through which passes the eye 10 of the bolt 7. Each of these hook members terminate in a hook portion 13 as shown in Figure 2.

Since the bolt 7 passes freely through the plates it can be turned to any position about its axis and since the engagement of the eyes 12 of the hook members 11 with the eye 10 of the bolt 7 is a loose and very free engagement, it is obvious that the hooks may be turned to a large number of different positions for the purpose of engaging objects which may occupy widely different relations to the jack head.

In the modification shown in Figure 4, the opposite ends of the plates 1 and 3 are provided with an opening through which passes loosely a bolt 14 similar to the bolt 7 and provided with a screw threaded portion 15 engaged by a nut 16. This bolt 14 has an eye 17 in which engages the eye 19 of a single hook member 18 provided with a hook end 20. This single hook member is or may be substantially identical with one of the hook members 11. At various times it is found desirable to employ a single hook member and in some cases the hook members at both ends of the plate may be similarly used.

In the form shown in Figures 1, 2 and 3, where a supporting bolt is provided only at one end of the device, the ears 4 are preferably bent over from the sides of the plate 3 leaving a tongue portion of the plate 3 through which the bolt 7 passes. In the form shown in Figure 4, both ends are formed alike while if only one bolt is employed the ears 4 may be formed at the end of the plate opposite to the bolt by turning down the whole end portion of the plate 3.

It is obvious that the device may be made in varying dimensions and that it can be attached to any usual form of jack head by removing one or both of the bolts 5, placing the plates in position, reinserting the bolts 106 and fastening them by means of the nuts 6. If it is desired to use the jack in the ordinary manner, it is not necessary to remove the attachment since the upper surface of the plate 1 is greater in area than the ordinary 110

jack head and it will ordinarily not be necessary even to remove the bolt 7. Obviously various changes may be made in the exact construction of the details without in any way departing from the spirit of the invention, which is to be regarded as limited only by the scope of the appended claims.

I claim as my invention:

1. An attachment for jacks comprising a plate having a pair of downturned ears at each end, bolts passing through said ears and with said plate forming means for engaging the upper and lower sides of a jack head and a lifting hook freely suspended from one end of said plate.
2. An attachment for jacks comprising a plate having a pair of downturned ears at each end, bolts passing through said ears and with said plate forming means for engaging the upper and lower sides of a jack head, a bolt supported freely in an end of
- 20

said plate and a lifting hook freely suspended from said bolt.

3. An attachment for jacks comprising a plate having a pair of downturned ears at each end, bolts passing through said ears and with said plate forming means for engaging the upper and lower sides of a jack head, a bolt supported freely in one end of said plate and terminating in an eye and a pair of lifting hooks freely suspended from said eye.

4. An attachment for jack heads comprising a plate, a second plate rigidly attached thereto and having downturned ears at each end, means associated with said ears for holding the plates in position on a jack head and a pair of lifting hooks freely suspended from one end of said plates.

In testimony whereof, I have hereunto 40
subscribed my name.

OSCAR PETERSON.
